MEANS FOR CONTROLLING ADVANCEMENT OF STOCK

Walkley B. Ewing, Grand Haven, Mich., assignor
to Ewing Development Company, Bay City,
Mich., a corporation of Michigan

Application August 3, 1946, Serial No. 688,302

4 Claims. (Cl. 164—6.5)

1

This invention relates to means for controlling the advancement of sheet material through a machine having cooperating punch and die assemblies for transforming the sheet material into sun screens, and the present application is a continuation in part of my co-pending applications Serial No. 488,611 and Serial No. 488,612, filed May 26, 1943, now Patent Nos. 2,405,197 and 2,405,198 patented August 6, 1946.

In general, the machine shown and described in the above identified co-pending applications includes a table over which the sheet material is advanced, a die member having a shearing edge in the plane of the table, a depressed step beyond the same, and a reciprocating punch assembly provided with a cooperating shearing edge. A spring pressed stripper bar carried by the punch assembly is movable to and from clamping engagement with the sheet material during reciprocation of the punch assembly and a spring pressed abutment or stop bar is also carried by the punch assembly and movable relative thereto in the path of the advancing sheet material.

In the operation of this machine the parts are so arranged and their movement with respect to each other so timed that the main stripper bar first moves into contact with the uncut sheet material in advance of the reciprocating punch and clamps the material to the table during the downward stroke of the punch. The abutment or stop bar for the sheet material is also carried by the reciprocating punch and is timed to move upwardly with the punch in its upward stroke and to reach the upper limit of its travel to lie in the path of the advancing sheet stock just prior to the upward movement of the main stripper bar which permits the sheet stock to quickly advance against the stop while the punch is in its retracted position.

When properly adjusted this arrangement of parts is efficient and satisfactory in operation, particularly where it is desired to employ the reciprocating abutment or stop member as a secondary punch or forming die.

However, in an effort to increase the speed of machines of this character and, accordingly, the output thereof, it has been found that occasionally, due to slight manufacturing inaccuracies or roughness of the sheared sheet material, the reciprocating abutment or stop member, in its upward movement, may not always completely strip from and clear the partially formed portions of the material in contact therewith prior to the upward movement of the main stripper bar and the resulting release of the sheet material for further advancement. Inasmuch as the sheet stock is being fed under slight pressure, the moment the main stripper bar releases the material, the cut portions thereof will be

2

forced more firmly against the face of the still upwardly moving abutment with the result that the material may be partially carried upwardly therewith. Such a condition may result in a jamming of the material within the machine causing a stoppage thereof. In part, this objectionable condition may be remedied by timing the relatively movable parts so that the main stripper bar remains in clamping contact with the sheet material until the upwardly moving abutment has been fully stripped of the material. However, such a solution unnecessarily limits the minimum time required for the machine to complete one cycle of operation.

10 15 Accordingly, one of the essential objects of the invention is to provide a machine wherein means is provided for controlling the advancement of stock so that it may advance in fast, short strokes through the machine.

20 Another object of the invention is to provide a machine wherein two means, preferably arranged in tandem, are provided for successively stopping or limiting the advancement of the sheet material.

25 Still another object is to provide a machine wherein one of the means above mentioned is carried by and movable with respect to a reciprocating punch assembly of the machine and the other means is stationary or positioned in

30 fixed relation thereto.

Other objects and advantages of the invention will become apparent from a reading of the following description taken in connection with the accompanying drawings in which:

35 Figure 1 is a perspective view of the main frame of the machine with a schematic assembly of the supporting structure for the punch actuating mechanism carried by said frame.

40 Figure 2 is a vertical sectional view through the machine at the center line thereof, with parts in elevation.

Figure 3 is a vertical sectional view through the slitter and folder punch and die assemblies.

45 Figure 4 is an enlarged fragmentary vertical sectional view through the slitter punch assembly and the cooperating die assembly when the punch assembly is in fully raised position, with the stripper bar in raised position to permit advancement of the sheet material and showing the fixed stop in its relative position to limit such advancement of the stock.

50 Figure 5 is a fragmentary elevational view of a portion of the machine, with certain parts broken away, and showing the fixed or stationary stop member for limiting the advancement of the sheet material.

55 Figure 6 is a fragmentary end elevational view of the parts shown in Figure 5.

60 Figure 7 is a horizontal sectional view through

the upright beam and bearings for the eccentric shafts for actuating the same.

Figure 8 is a fragmentary elevational view of the upright beam and bearing sleeves illustrated in Figure 7.

Figure 9 is an end view of the structure illustrated in Figure 8.

Figure 10 is an elevational view of the driving means and supports therefor.

Figure 11 is an end elevation of the structure illustrated in Figure 10.

Figure 12 is a horizontal sectional view taken substantially on the line XII—XII of Figure 11 and shown partly in dotted lines to disclose the bed therewith.

Figure 13 is an enlarged front elevation of a small portion of a preferred form of the sun screen made by the machine.

Figure 14 is a cross-sectional view taken on the line XIV—XIV of Figure 13.

Figure 15 is an enlarged plan view of a portion of a slotted blank used in making the sun screen illustrated in Figures 13 and 14, and

Figure 16 is a perspective view of the blank of Figure 15 partially folded into the screen structure illustrated in Figures 13 and 14.

The sun screen produced by a machine embodying the present invention is formed by slitting and folding a single sheet of material and consists of a series of parallel strips 2 of elongated cross-section which are vertically superposed at equal intervals not greatly exceeding, and preferably approximately equal to, the width of a strip and are inclined, preferably at least 45°, and perhaps as much as 75°, to the general plane of the screen, i. e. to the vertical.

As shown, each individual strip 2 extends horizontally across the screen and lies in a single plane. Preferably each strip 2 is off-set regularly in the same direction at equal intervals along its length, as at 3, the distance of off-set not exceeding about three-fourths the width of the strip and being advantageously about one-half such width. The strips 2 are joined together by vertical rows of legs 4 formed of sheet material integral with that of the strip, each leg having a width substantially equal to the regular off-set distance of each strip, i. e., not greater than about three-fourths the width of the strip and connecting a front portion 5 of the strip with the corresponding oppositely off-set rear edge 6 of an adjacent strip. The rows of legs 4 are ordinarily spaced apart a distance large in comparison to the intervals between the adjacent strips. As will be seen from the drawings, the legs 4 are inclined to the general plane of the screen and are also rather sharply inclined to the strips to which they are attached. The legs in any given row are ordinarily in the same or in parallel vertical planes, and preferably have their centers all in the same vertical line, in order to give a generally rectangular appearance to the screen.

While the sun screen is illustrated with only two off-sets per strip and two rows of legs, it will be appreciated that it may comprise any number of off-sets and corresponding rows of legs to form a screen of the desired dimensions. In general, the width of a strip will be from one-eighth to one-half inch and the distance between rows of legs one-half to five inches, although other sizes are equally possible. The screen is usually fabricated of thin sheet metal but may also be formed of other flexible, strong material such as synthetic plastic sheet.

In making the sun screen, the sheet material or blank from which the screen is to be fabricated is first slit and is then formed into the screen. Preferably this blank comprises a sheet substantially rhomboidal in shape and having therein, on the bias to an edge thereof, a plurality of like parallel series of parallel regularly, off-set, overlapping slits, said slotted sheet thus defining a plurality of parallel continuous regularly off-set members inter-connected at their corresponding oppositely off-set portions by leg members.

As shown in Figure 15 the parallel slits are all disposed on the bias to the lateral edges of the said sheet and are arranged in a plurality of like parallel series as at 8 and 8'. The individual lines within a series are regularly off-set a distance which does not exceed about three-fourths the distance between corresponding lines of adjacent series and overlap at their off-set portions a distance which does not greatly exceed, and need not equal, the distance between corresponding lines of adjacent series. As a result of this slitting, there are formed parallel continuous regularly off-set strip members 2 inter-connected at their corresponding oppositely off-set portions by leg members 4.

The blank slotted as described is formed into a sun screen by successively displacing the strip member diagonally downwardly and backwardly in the bias direction to support the strip in substantially parallel planes and to cause the leg members to become inclined to the strip and to the general plane of the resulting screen. A partially folded blank showing two of the strip members already displaced into position is illustrated in Figure 16.

The displacement of the strip members 2 and the concurrent formation of the legs 4 may be rendered more accurate by defining on the blank fold lines 9 to mark the point of juncture of the leg members 4 with the strip 2 either by suitably crimping the blank or by other means. The fold lines 9 are ordinarily oblique to the long edges of the strip 2 and are preferably in the same or parallel planes.

The screen may be fabricated by extremely simple means from a single sheet of material, and can be made in any desired size. The metal in the screen is not under stress, having been merely folded into position. The structure presents only smooth, flat surfaces and hence collects little dust or dirt and can be easily cleaned. If desired, it may be rolled up for shipping.

Referring now to the machine for making the sun screen, reference character A represents the main frame having a base 10, uprights 11 and 12 respectively at opposite ends of the base, and a top 13 mounted upon the uprights. B is an auxiliary frame mounted within the main frame A at the bottom thereof and constituting a support for a die assembly C and feed bed D.

Parallel, horizontal shafts 15, 16 and 17, respectively, are disposed obliquely to the longitudinal median line of the main frame and are supported from the top 13 thereof and adapted to be driven from a motor (not shown) or other suitable power plant upon the top 13 of the frame. The shafts 15, 16 and 17 are respectively mounted in suitable bearings within sleeves 21 suspended by a bracket 22 from a plate 23 rigidly secured to the under side of the top 13 of the frame.

In the present instance, the shaft 15 is a rotating shaft while the shafts 16 and 17, respectively,

merely oscillate and are driven in unison from the shaft 15. As shown, a double crank arm 24 is carried by the shaft 17 and is connected by rods 25 and 26, respectively, to cranks 27 and 28, respectively, carried by the shafts 15 and 16. Thus, rotary movement of the shaft 15 will be translated by the crank 27, rod 25 and crank 24 into oscillating movement for the shaft 17, and such oscillating movement of the shaft 17 will be transmitted by the rod 26 and crank 28 to the shaft 16 so that both shafts 16 and 17 will oscillate in unison.

The shafts 16 and 17 are provided with eccentric portions 29 and 30, respectively, carrying bearings for tubular sleeves 31 and 32 from which a vertical I-beam 33 is suspended in substantially vertical alignment with the auxiliary frame B for actuating simultaneously a slitter punch assembly E and a folder punch assembly F relative to the die assembly C.

The slitter punch assembly E reciprocates vertically relative to the die assembly C to provide slits such as 8 and 8' in the sheet material, while the folder punch assembly F oscillates relative to the die assembly to fold portions of the sheet material beside the slits in the louver and interconnecting legs such as 2 and 4, respectively.

The folder punch assembly F is beside but separate from the punch assembly E and is secured to a depending leg or flange 34 of the I-beam 33 so as to oscillate in unison therewith as such beam is actuated by the eccentric 29 and 30 of the shafts 16 and 17. A yoke 35 straddles the punch assembly E and the base 36 of the I-beam 33 and cooperates with said base for translating the oscillating movement of the eye beam into a vertical reciprocating movement for the punch assembly E. In this connection it will be noted that the punch assembly E is guided vertically by means of pins 37 mounted upon the auxiliary frame B.

The die assembly C has a base 40 mounted upon the auxiliary frame B beneath the feed bed D and includes a slitter die H and a folder die J. Preferably the slitter die H is clamped between sections 41 and 41' of a suitable holder M on the base 40 at the inner end of the feed bed D while the folder die J is anchored upon the outer section 41' of the holder for the slitter die H. Any suitable means such as a clamp 42 and bolts 43 and 44, respectively, may be employed to fasten the holder sections 41 and 41' to the base 40.

The slitter die H has plate-like blades 50 and plate-like spacers 51 beside said blades. The upper ends of the spacers 51 are flat and are preferably arranged in stepped relationship to each other and to the upper end of the slitter blade 50.

The folder die J comprises a series of block-like members which are anchored by bolts 66 upon the outer sections 41' of the die holder M in stepped relation to the spacers 51 and are provided at their outer edges with stepped undercut portions 67 and 68.

The punch assembly E includes a holder 70 having a head 71 between the base 36 of the I-beam 33 and the lower arm 35' of the yoke 35, and clamping sections 73 and 76, respectively, which are carried by the head 71 within a recess 74 in the lower forward corner thereof. The slitter blades 58 of the punch assembly are disposed in upright, staggered, overlapping and parallel relation to each other between plate-like spacers. Any suitable means such as bolts 78 may be used to hold together the clamping sections 73 and 76 and any suitable means such as

bolts 79 may be used to fasten the clamped sections 73 and 76 to the head 71.

When assembled between the clamping sections 73 and 76, the lower working ends of the slitter blades 58 project slightly below the lower ends of the spacers so as to overlap in scissors-like formation the cutting edges of the slitter blades 50 on the downward stroke of the punch holder 70 to effect the slitting operation.

The folder punch assembly F comprises a die holder 82 rigid with the depending flange 34 of the I-beam 33, and folder blades 83, 84 and 85, respectively within a recess 86 in a lower end of the holder 82 are held in assembled relation therein by means of a clamping wedge 87 that is bolted or otherwise suitably connected to the holder. As shown, the blades 83 to 85 inclusive are arranged overlappingly and inwardly inclined with the lower working ends thereof in downwardly stepped relation for mating engagement with the top and under-cut portions 67 and 68 of the die J.

In the present instance, the sheet material X is fed from a power driven roll thereof (not shown) onto and along the feed bed D to the slitter punch and die assemblies E and H respectively which collectively constitute the first station where the slits 8 and 8' are successively formed. Such material X is then advanced to the folder punch and die assemblies F and J which collectively constitute the second station where portions of the material beside the slits are folded into inclined relation to the sheet material to form the louvers 2 and legs 4 of the sun screen.

A stripper bar 90 is movable vertically within a suitable recess 91 in the lower end of the clamping section 72 of the holder 70 for engagement with the sheet material X to partially control the advancement thereof to the two stations above mentioned. As shown, this stripper bar 90 is connected to the lower end of a vertical bolt 92 slidably mounted in the clamping section 72 and having the head 93 thereof within a recess 94 in said clamping section. A coil spring 95 is sleeved upon the bolt 92 within an enlarged recess 96 in the clamping section 72 and in a similar recess 97 in the stripper bar 90 and urges the latter downwardly upon the sheet material X to hold it against advancement into the machine. However, when the head 93 of the bolt 92 engages the bottom of the recess 94 in the clamping section 72 during the upward movement of the punch holder 70, the stripper bar 90 will be raised to permit advancement of the sheet material from the first station to the second station.

Cooperating with the stripper bar 90 to temporarily limit advancement of the sheet material at the first station preparatory to the slitting operation, is a stationary plate 75 extending transversely of the machine between the uprights 11 and 12 and secured thereto at its ends in any suitable manner (not shown) or may be supported from any other stationary portion of the machine, such as the fixed die assembly C. This plate is provided along its lower edge with a laterally extending foot portion constituting a stop 100 extending downwardly into the path of the advancing sheet material X to limit the advance thereof at the first station and prior to the downward slitting stroke of the punch assembly E. The operating face of the stop 100 is preferably formed with regularly off-set portions along its length (not shown) to conform to the shape of a slotted blank, such as is shown in Figure 15.

In order to prevent lateral bending movement of the plate 75 and stop 100 with respect to the reciprocating punch assembly E, the bolts 78 which hold together the clamping sections 73 and 76 of the punch assembly may be rewardly extended through elongated openings 101 in the plate 75 and provided with shouldered nuts 77, thereby securing the plate 75 to the punch holder against lateral movement with respect thereto but premitting the relative reciprocating movement of the punch assembly.

By reference to Figure 4 of the drawings, it will be noted that the stop 100 extends downwardly relative to the advancing stock X and the stepped die members 51 only sufficiently to engage the advancing stock when the slitter punch E and the stripper bar 90 are in retracted position but not sufficiently to interfere with the further advancement of the slitted material toward the second station where the folding operation takes place.

During the initial upward movement of the holder 70, the stripper bar 90 will be held down by the spring 95 in engagement with the sheet material X to prevent it from advancing. Sufficient clearance is provided between the lower face of the stop 100 and the spacers 51 to permit advancement of the sheet material therebetween, but such advancement is still prevented by the stripper bar 90 clamping the material X to the table D. During the final upward movement of the punch holder 70, the stripper bar 90 is raised out of contact with the sheet material to permit its advancement. The sheet material will then be advanced until the forward edge of the sheet abuts the stop 100.

Upon the initial downward stroke of the holder 70, the stripper bar 90 will move downwardly to again engage and hold the sheet material against advancement. Thus, the sheet material is alternately held and released for advancement during reciprocation of the slitter punch assembly E.

In operation, the shafts 16 and 17 are oscillated in unison when the shaft 15 is rotated, hence the I-beam 33 carried by the eccentric portions 29 and 30 respectively of said shaft 5 is likewise oscillated.

During the downward swinging movement of the beam 33, the folder punch assembly F carried thereby will be moved in an arc down and back relative to the cooperating folder die assembly J to effect a folding operation and the punch assembly E will be moved vertically downwardly by the base 36 of the beam to cooperate with the die assembly H to effect a slitting operation. Thus, a slitting operation and a folding operation are performed simultaneously during the downward swinging movement of the beam 33.

During the upward movement of the beam 33, the folder punch assembly F will be moved in an arc upwardly and forwardly away from the die assembly J and the punch assembly E will be moved by the lower arm 33' of the yoke 35 vertically and upwardly away from the die assembly H. Consequently, the punch assemblies E and F will be raised simultaneously. In fact, reciprocating movement is translated to the slitter punch assembly E from the oscillating beam 33 while oscillating movement is imparted directly to the folder punch assembly F by said beam.

The sheet material to be formed into sun screens is fed onto and along the feed bed D to the stripper bar 90. When the punch assembly E is first fully raised by the yoke 35 and beam 33, as above described, the sheet material will be

advanced until the leading edge thereof abuts the adjacent face of the stop 100, as clearly illustrated in Figures 3 and 4 of the drawings.

Upon the downward stroke of the slitter punch assembly E relative to the die assembly H the co-operating cutting edges of the blades 58 and 59 will overlap one another to form a slit in the sheet material. Consequently, the blade 58 will depress below the upper end of blade 59 that portion of the material between the forward end thereof and the slit so formed. During this operation, the forward edge of the material which has been in abutting engagement with the stop 100 will be cleanly stripped therefrom. Throughout the operation just described the stripper bar 90 is held by the spring 95 in firm engagement with the sheet material to temporarily prevent further advancement thereof on the feed bed.

When the punch assembly E is again fully raised, the sheet material will be advanced until the rear edge of the formed slit abuts the adjacent face of the stop 100 and such advancement of the material will cause the depressed portion thereof, that is, the portion between the forward end of the sheet and the forward edge of the formed slit, to be advanced beneath the stop 100.

During the next downward stroke of the punch assembly E relative to the die assembly H, a second slit will be formed by the blades 58 and 59 in the sheet material in staggered, overlapping, and parallel relation to the first mentioned slit and the portion of the material between the first and second slits will be depressed below the rear edge of the second formed slit.

When the slitter punch assembly E is again fully raised, and accordingly, the stripper bar 90, the sheet material will be advanced until the rear edge of the second formed slit abuts the adjacent face of the stop 100 and such advancement of the material will cause the first mentioned depressed portion of the material to be advanced over the folder die J, and will cause the second mentioned depressed portion to be advanced beneath the stop 100.

Thus the sheet material will be successively advanced a distance equal to the width of a depressed portion each time the punch assembly E is fully raised during vertical reciprocation thereof.

After a sixth slit is formed, as above described, in the sheet material by the blades 58 and 59, the material will have advanced further until the first mentioned depressed portion of the material, that is, the portion between the forward end and the first slit, is positioned between the working portions 67, 83, 84, 85, respectively, of the punch and die assemblies F and J.

When a seventh slit is being formed in the sheet material, the punch and die elements 67, 83, 84, and 85, respectively of the assemblies F and J will fold the first mentioned depressed portion of the material downwardly and backwardly to provide an inclined louver 2 and leg 4. Thereafter, during each downward stroke of the beam 33, a folding operation to produce a louver 2 and leg 4 occurs simultaneously with a slitting operation as the sheet material is advanced through the machine.

It will be appreciated that the stationary stop member 100 for the advancing stock, being stationary with respect to the movable slitting punch E and stripper bar 90 as well as in fixed, vertically spaced relation to the stepped die members 51, provides for the rapid advancement of the material through the machine without danger of the

partially formed portions of the blank binding or jamming against the moving parts thereof. In addition, the time required for machines of this type to complete one cycle of operation has been reduced, thus increasing the overall speed and out-put thereof.

It will be obvious to those skilled in the art that various modifications in construction and design may be made in the invention as herein shown and described without departing from the spirit or scope thereof which is to be limited only by the appended claims.

What is claimed and desired to be secured by Letters Patent is:

1. In a machine for transforming a sheet of material into a predetermined configuration, the combination comprising: a frame; a table supported upon said frame over which said sheet material is advanced unidirectionally; a die at one end of said table, said die having a shearing edge in the plane of the table and a depressed step adjacent to said shearing edge; a punch having a slitting shear cooperable with said shearing edge for slitting said sheet material and adapted to press the sheared portion of said sheet against said step, said punch being reciprocably supported upon said frame above said die; a stripper bar reciprocably supported upon said punch for alternately checking and permitting the advancement of said sheet material; resilient means urging said stripper bar toward said sheet material; and a stationary stop secured to said frame and extending into the path of the sheet material but vertically spaced from the depressed slotted portion thereof.

2. In a machine for transforming a sheet of material into a predetermined configuration, the combination comprising: a frame; a horizontal table supported within said frame over which said sheet material is advanced unidirectionally; a die assembly secured to one end of said table, said die having a plurality of shearing edges in the plane of the table and a plurality of depressed steps remote from said table; a punch assembly having slitting shears and folding plates, said punch assembly being vertically, reciprocably supported by said frame above said die assembly, said slitting shears operably engaging said die assembly shearing edges for slitting and depressing a portion of said sheet material successively against said steps, and said folding plates cooperating with said depressed steps for shaping said sheet material slotted portions; a stripper bar reciprocably supported upon said punch assembly for alternately checking and permitting the advancement of said sheet material; a resilient means urging said stripper bar toward said sheet material; and a stationary stop secured to said frame, positioned between said slitting shears and said folding plates and extending into the path of the sheet material on the table, all so arranged and constructed that said sheet material is prevented from advancing while being slitted and folded.

3. In a machine for transforming a thin sheet of material into a predetermined configuration including a plurality of substantially parallel, spaced portions, the combination comprising: a frame; a horizontal table supported within said frame upon and along which said sheet material is advanced under continuous unidirectional pressure; a die assembly secured to said frame and adjacent to one end of said table, said die having a series of discontinuous, parallel shearing edges arranged in the plane of the table and a plurality of depressed steps extending away

from said shearing edges and said table; a punch assembly having a slitting head and a folding head, said assembly being reciprocably mounted upon said frame above said die assembly for vertical movement with respect thereto, said slitting head having shearing plates cooperating with the said shearing edges of said die assembly for slitting said sheet material and depressing the slotted portions thereof against the first of said depressed steps when said punch assembly is moved downwardly, and said folding head having folding plates cooperating with said depressed steps for shaping said sheet material slotted portions when said punch assembly is moved downwardly; a stripper bar vertically reciprocably supported upon said slitting head for alternately checking and permitting the advancement of said sheet material, said stripper bar extending slightly below the lower edges of said shearing plates when said punch assembly is in the raised position; a resilient means urging said stripper bar into the extended position; and a stationary stop secured to said frame slidably engaging said slitting head and positioned between said slitting head and said folding head, said stop extending into the path of the sheet material on the table but vertically spaced from the slotted portion thereof depressed against said first step; all arranged and constructed so that said sheet material is engaged first by said stripper bar and then by said shearing plates when said punch assembly is moved downwardly and said sheet material may be successively advanced each time said punch assembly is raised high enough to lift said stripper bar away from said sheet material.

4. In a machine for transforming a sheet of material into a predetermined configuration, the combination comprising: a frame; a horizontal table supported within said frame over which said sheet material is advanced unidirectionally; a die assembly secured to one end of said table, said die having a plurality of shearing edges in the plane of the table and a plurality of depressed steps remote from said table; a punch assembly having slitting shears and folding plates, said punch assembly being vertically, reciprocably supported by said frame above said die assembly, said slitting shears operably engaging said die assembly shearing edges for slitting and depressing a portion of said sheet material successively against said steps, and said folding plates cooperating with said depressed steps for shaping said sheet material slotted portions; a stripper bar reciprocably supported upon said punch assembly for alternately checking and permitting the advancement of said sheet material; means for urging said stripper bar toward said sheet material; and a stationary stop secured to said frame, positioned between said slitting shears and said folding plates and extending into the path of the sheet material on the table, all so arranged and constructed that said sheet material is prevented from advancing while being slitted and folded.
